Primary Examiner — Michael A. Pratt*(74) Attorney, Agent, or Firm* — Husch Blackwell LLP**(57) CLAIM**

The ornamental design for a baseball catcher's helmet, as shown and described.

DESCRIPTION

FIG. 1 is a left front perspective view of baseball catcher's helmet, showing my new design;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof; and,

FIG. 8 is a left front exploded perspective view showing a removable portion of the helmet for reference only.

The broken lines in the drawings depict portions of the baseball catcher's helmet that form no part of the claimed design.
